UNITED STATES PATENT OFFICE

2,564,545

PIVOT FOR OVERHEAD DOORS

William Rochford, Houston, Tex.

Application March 6, 1946, Serial No. 652,411

2 Claims. (Cl. 16—129)

1

This invention relates to improvements in bracing means therefor for overhead garage doors.

An object of the invention is to provide improvements in bracing means therefor for overhead garage doors, which construction eliminates the need of trusses to prevent the door from sagging when in upward position, lock, bumpers and door handle.

Another object of the invention is to provide an improved suspension means therefor for overhead garage doors, which will permit its use for doors of varying width, due to the use of adjustable offset pipe arms for supporting the door in raised or lowered position.

A further object of the invention is to provide an improved rotatable clamp for supporting adjustable offset pipe arms which will be secured to an overhead garage door for swingably supporting the same in open or closed position.

A still further object of the invention is to provide an improved bracing device for overhead garage doors which will be highly efficient in use, and relatively inexpensive to manufacture and produce.

Other objects will appear as the description proceeds.

In the accompanying drawings which form a part of this application:

Figure 1 is a plan view of the improved overhead garage door hardware shown attached to the side walls of a garage, the side walls being in horizontal section;

Figure 2 is a plan view of one of the overhead garage door hangers in position in a garage and secured to the garage door, the side wall of the garage being shown in horizontal section.

Figure 3 is a vertical sectional view taken on line 3—3 in Figure 1 and showing a truck in dotted lines in the garage;

Figure 4 is an enlarged side elevation of one of the overhead garage door hangers with biasing spring attached, and a portion of the garage door being in section to show the method of attaching the hanger arms to the door;

Figure 5 is a sectional view taken on the line 5—5 of Figure 4;

Figure 6 is a sectional view of the pipe arm clamping and supporting bracket;

Figure 7 is a vertical sectional view through a modified form of pivoted arm supporting clamp;

Figure 8 is a sectional view taken on the line 8—8 of Figure 4;

Figure 9 is a plan view of the bearing pivot for the arm supporting brackets;

Figure 10 is a side elevation, partly in section 55

of the bearing pivot for the arm supporting brackets;

Figure 11 is a sectional view taken on the line 11—11 of Figure 4, and

Figure 12 is a view taken on the line 12—12 of Figure 4.

Like characters of reference are used throughout the following specification and the accompanying drawings to designate corresponding parts.

In carrying out the invention, there is provided a pair of similarly constructed rotatably supported pipe arm supporting brackets generally denoted by the reference numeral 1, adapted to be supported on the opposite inside wall 2 and 3 of a garage. The garage illustrated will include studding 4 and siding 5, and a door opening 6 in which the overhead door 7 is adapted to be positioned when in lowered or closed position.

The bracket supporting boards 8 will be secured between two adjacent studs 4 by means of the nails or fasteners 9. The preferred form of the bracket will include a bearing pivot having a base 10 secured to the board 8 by means of the bolts 11, and formed with the outwardly extending pivot shank or pin 12, which is formed adjacent its outer end with the annular bearing shoulder 13 and reduced terminal end 14. The outer end of the pivot shank or pin 12 is provided with a threaded socket 15 adapted to receive the locking bolt 16, which in turn supports the bracket engaging locking washer 17.

The rotatable pipe arm clamping and supporting brackets 1 comprise the cooperating clamping members 18 and 19 which are formed with the parallel extending grooves 20 and 21 for receiving the inner ends of the offset pipe arms 22 and 23 which are connected to the garage door 7 for supporting the same. The bolts 24 will extend through aligned apertures in the brackets or clamping members 18 and 19 for clamping the pipe arms 22 and 23 in fixed position therein. The locking bolt 16 and washer 17 will be used to hold the parts of the brackets in position while the bolts 24 are being secured in place.

A modified form of clamping brackets is shown in Figure 7, and includes a flanged base 40 which supports the inner of the two similar clamping members 27 and 28 in which are formed the parallel extending pipe arm receiving grooves 29 and 30, and the aligned threaded centrally disposed apertures 25 and 26. The clamping members are adapted to be held in place by means of the threaded bolt 31 extending through the threaded aperture 25 in the outer member and

into the threaded aperture 26 in the inner member.

As shown best in Figures 9 and 10 of the drawings, the bracket supporting base 10 has four apertures 33 which are formed to receive bolts 5 for securing the same in place.

The pipe arms 22 and 23 for supporting the garage door 7 are formed of regulation standard tubular pipes of the desired diameter and extend parallel at their inner ends to be received in the clamping bracket 1, and are bent laterally intermediate their ends, and terminate in the offset parallel extending outer ends which are externally threaded as at 38, and are adapted to extend through apertures formed through the door 7. Suitable reinforcing and backing blocks 39 are provided for the outer end of each arm 22 and 23, said blocks being formed with threaded central apertures through which the arms 22 and 23 extend, and are also apertured to receive the four bolts 41 extending through the block and the garage door 7.

A sleeve 42 having an eye 43 and secured to each upper pipe arm 22 on the opposite sides of the garage, and supports a section of chain 44 and a connected heavy coil spring 45 which is secured in an eye 46 formed in the offset plates 41 secured by the bolts 48 to the anchoring plate 49 secured to adjacent studs 4. The spring will be adjustably tensioned to permit the easy opening and swinging of the garage door to its uppermost or open position, and vice versa.

The use of regular round pipe stock and bending the same to provide the offset outer parallel door attaching ends provides for ready and efficient turning of the arms to the proper position to support garage doors of varying width. The use of any other arm construction other than round pipe will not permit an offset construction to be rotated to accommodate the use of the arms to support doors of different width.

Furthermore, the offset construction of the pipe arms provides for the turning of the pipe arms 22 and 23 in their hinges or brackets, to allow for the offset in the construction of the garage door opening without requiring fabrication on the job.

In the event one side jamb is out of vertical alignment with the other side jamb, the garage

door may be adjusted or canted to the door in its frame, by merely pulling in or out on the proper arm and locking it in its adjusted position, thereby centering the door in the out-of-line frame.

While the preferred embodiment of the instant invention has been illustrated and described, it will be understood that it is not intended to limit the scope of the invention thereto, as many minor changes in detail of construction may be resorted to without departure from the spirit of the invention.

Having thus described my invention what I claim as new and desire to secure by Letters Patent of the United States is:

1. A bracing device for overhead garage doors including a bracket support adapted to be secured to the inside wall of a garage, said bracket support consisting of a pivot plate, a pair of cooperating clamping members mounted on said pivot plate and having oppositely disposed, longitudinal complementary grooves in said clamping members, longitudinally adjustable tubular arms having one pair of ends in said grooves, said arms being round in cross section and said grooves defining sockets wherein said arms are mounted for rotative adjustment about the longitudinal axes of the sockets, secured by said clamping members, and backing blocks for securing on a garage door, the other ends of said arms being terminally and rotatively adjustably secured to said blocks.

2. The combination of claim 1, wherein said tubular arms consist of a longitudinal central portion and oppositely bent parallel end portions, said other ends of said arms being threadedly secured in said backing blocks.

WILLIAM ROCHFORD.
